UNITED STATES PATENT OFFICE.

JOHN McCALLUM, OF WALBRIDGE, OHIO.

REMOTE-CONTROL DEVICE FOR RAILROAD CARS.

Application filed July 15, 1925. Serial No. 42,686.

My invention has for its object to provide a remote control means for controlling the speed of one or more rail cars, such as, railroad freight cars. The invention is particularly of advantage when used in freight yards for switching purposes, particularly, for regulating the distances that the cars may run free after they have been impelled to move by any force. The car may receive its momentum from the railroad engine or from an inclined track or from any other force translating means.

To illustrate a practical application of the invention, I have selected a structure containing the invention and shall describe it hereinafter. The structure selected is shown in the accompanying drawings.

Figure 1 of the drawings illustrates a top view showing one end of the control device. Fig. 2 illustrates a view of a section taken on the line 2—2 indicated in Fig. 1. Fig. 3 is a diagrammatic view showing a plurality of spaced controlling means for regulating the speed of a car as it moves along a track of considerable length. Fig. 4 is a top view showing the construction of the ends of the device. Fig. 5 is a view of a section taken on the line 5—5 indicated in Fig. 4.

Of the remote controlling device embodying my invention, the one shown in the drawings has a plurality of pairs of bars 1 that extend along the rails 2 of the tracks over which the cars run and means is provided for raising the bars so that they will engage the wheels 3 of the cars. They, preferably, engage the flanges 4 that move faster than the surfaces of the wheel that roll on the top of the rails 2 and thus the bars operate as brakes on the wheels. The bars are preferably so formed as to be wedge shaped in their cross section, and wedging edges being disposed along the sides of the tops of the rails and so as to enter between the flanges and the rails. The bars are thus located between the parallel rails and are preferably raised to make contact with the wheels. They are located on wedges 5 that engage inclined surfaces 6 formed on the parts of the bars 1. The bars have abutment lugs 7 that engage the webs of the rails 2 so that when the wedges 5 are pushed under the bars 1, the bars will not tilt or be crowded under the tops of the rails. The bars 1 are held in place between brackets 8

that are supported on the guard rail 9. The guard rails 9 substantially enclose the bars 1 between the guard rails 9 and the T-rails 2. The brackets 8 may be formed of straps of metal that are bent at their ends and bolted to the guard rail 9. The bars 1 are held from endwise movement by means of the blocks 10 that may be formed integral with the brackets 11 that are secured to the rails and are located at the ends of the guard rails 9 and the bars 6 and in line with the bars.

The wedges 5 extend through openings 12 formed in the guard rail 9. They slide upon the bottom flanges 13 of the guard rails. They may be actuated by levers such as the levers 14 which are connected through the links 15 and the bell crank levers 16 to the wedges 5 to raise and lower the bars 1 as may be desired to frictionally engage with more or less pressure, the wheels 3. Thus when a car is moving along the bars its speed may be reduced to any desired rate. The amount of reduction of the speed of the car will ordinarily depend on the distance that it is desired to allow the car to run free. Also if desired the car may be stopped on the bars 1. This will depend upon the frictional engagement between the bars 1 and the flanges of the wheels of the car. As shown in Fig. 3 a plurality of pairs of bars 1 may be used for regulating the speed of the car. The plurality of pairs of bars may be used on the single track or may be used on branching tracks to control the speed of the car.

I claim:

1. In a remote speed control for rail cars, a wedge bar located along the rail and having a wedging edge for engaging the flanges of the wheels of the cars, and means for operating the wedge bar to engage the flanges of the wheels.

2. In a remote speed control for rail cars, a wedge bar located along the rail and having a wedging edge for engaging the flanges of the wheels of the cars, and means for raising the wedge bar to engage between the flanges of the wheels and the rail.

3. In a remote speed control for rail cars, a pair of wedge bars located along the rails and having wedging edges for engaging between the flanges of the wheels and the rails, a means operable to raise the pair of

wedge bars to cause its wedging edge to engage between the flanges of the wheels and the rails.

4. In a remote speed control for rail cars, a pair of wedge bars located along the rails and having wedging edges for engaging between the flanges of the wheels and the rails, a plurality of wedges slidably located beneath the wedge bars for raising the wedge bars and means for operating the wedges.
5. In a remote speed control for rail cars, a plurality of pairs of wedge bars located along the rails and having wedging bars for engaging between the flanges of the wheels and the rails, a means operable to raise each pair of wedge bars to cause its wedging edge to engage between the flanges of the wheels and the rails.

In testimony whereof I have hereunto signed my name to this specification.

JOHN McCALLUM.
